Primary Examiner — Bridget L Eland(74) *Attorney, Agent, or Firm* — JCIPRNET(57) **CLAIM**

The ornamental design for a cable storage case, as shown and described.

DESCRIPTION

FIG. 1 is a perspective view of a cable storage case showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded view thereof;

FIG. 9 is an exploded view thereof shown in a state of use with environment; and,

FIG. 10 is another perspective view thereof shown in a state of use with environment.

The broken lines in FIGS. 9 and 10 are directed to environment and form no part of the claimed design.
